CLAIM

I claim the ornamental design for the finger guard, as shown.

DESCRIPTION

FIG. 1 is a front view of a finger guard;

FIG. 2 is a top view of the finger guard;

FIG. 3 is a back view of the finger guard;

FIG. 4 is a bottom view of the finger guard;

FIG. 5 is a left side view of the finger guard, the right side view
being a mirror image; and,

FIG. 6 is a perspective view of the finger guard.
